UNITED STATES PATENT OFFICE.

CHARLES W. BLAKE, OF PLEASANTVILLE, NEW JERSEY.

BOAT-LAUNCHING MECHANISM.

Application filed October 18, 1922. Serial No. 595,329.

To all whom it may concern:

Be it known that CHARLES W. BLAKE, a citizen of the United States, residing at Pleasantville, in the county of Atlantic and State of New Jersey, has invented certain new and useful Improvements in Boat-Launching Mechanisms, of which the following is a specification.

This invention relates to boat launching mechanisms and has for an object to provide a device for launching a boat, more specifically a life boat, from the deck of a vessel, and embodying new and improved means for launching the boat in the minimum duration of time and the employment of the minimum number of persons for effecting such launching.

A further object of the invention is to provide a boat launching mechanism including spaced davits between which the boat is normally secured upon the deck of the vessel, with improved means for swinging the davits outboard, controlled from and actuated by the weight of the boat itself when manually released from the chocks.

A further object of the invention is to provide chocks which are secured to the deck of the vessel with additional means for securing the boat rigidly and securely upon such chocks for ordinary storage and transportation, and with improved means for simultaneously releasing the boat from such securing mechanism and projecting it off from the chocks, whereby the weight of the boat exerted upon the falls actuates the mechanism which swings the davits from normal to outboard position, carrying therewith the boat, so that by the weight of the boat the davits are actuated to swing the boat outboard, either with its load of passengers, or to be loaded after being swung outboard substantially on a level with the deck.

A further object of the invention is to provide an improved type of manual control for controlling the several agencies, instrumentalities, functions, and activities of the several mechanical features and structural units to be hereinafter more fully described.

With these and other objects in view, the invention comprises certain novel parts, units, elements, mechanical combinations, movements, functions and interrelations, as disclosed in the drawings, together with the mechanical equivalents thereof, as will be hereinafter more fully described and claimed.

In the drawings:

Fig. 1 is a perspective view of the improved boat launching mechanism with a boat in storage or carrying position thereon. 60

Fig. 2 is a top plan view of the boat launching mechanism with the boat removed and the davits shown in section.

Fig. 3 is a view, partly in side elevation and partly in vertical section, of the mechanism, with the boat shown in dotted lines, as indicated by line 3—3 of Fig. 2. 65

Fig. 4 is a perspective view of one of the chocks and its supporting and actuating accessories. 70

Fig. 5 is a vertical transverse sectional view taken on the line 5—5 of Figs. 2 and 3, with the boat shown rigidly secured to and supported upon the chocks.

Fig. 6 is a similar view, with the chocks 75 tilted to boat releasing position, and the boat shown swung toward the outer position with its weight thrown upon the falls.

Fig. 7 is a diagrammatic sectional view showing the action of the weight of the boat 80 on the falls in the actuation of the davits.

Fig. 8 is a sectional view taken on line 8—8 of Figs. 2 and 3, showing the initial position of the davits in full lines and the outboard positioned in dotted lines. 85

Fig. 9 is a sectional view of the modified type of apparatus for actuating the band brakes.

Like characters of reference indicate corresponding parts throughout the several views. 90

The improved boat launching mechanism which forms the subject matter of this application is adapted to be mounted upon the deck of a vessel. At 10 a structure is indicated as a deck, being shown, however, in its simplest form and not intended in any way to limit the invention, but merely by way of illustration. Adjacent the margin of the deck uprights 11 and 12 are mounted, to 95 which are pivoted respectively davits 13 and 14 by means of the bolts 15 and 16, respectively, or by any other usual and approved hinging or fulcruming means.

Extending longitudinally between the uprights 11 and 12 is a shaft 17 journalled to rotate freely when released in the said uprights 11 and 12. This shaft 17 carries pinions 18 and 19 which respectively intermesh with segmental racks 20 and 21 formed 110 rigid and preferably integral, respectively, with the davits 13 and 14, and curved as arcs

about the fulcrums 15 and 16, so that as the pinions 18 and 19 rotate, they cause the davits 13 and 14 to swing from the normal or upright position shown in full lines at Fig. 8, to the outboard position shown in said figure by dotted lines. These pinions 18 and 19 are rigidly secured to the shaft 17, so that the davits 13 and 14 will swing uniformly and in consonance outwardly to swing the boat from the storage position shown at Fig. 5 along the path indicated at Fig. 6.

Mounted also upon the shaft 17 is a brake drum 22, about which is a brake band 23. The brake band is controlled from the manual lever 24 fulcrumed at 25 upon the deck 10 with the latch 26, which may be swung upon its pivot to the position indicated as 26' in Fig. 2, to release said lever. The lever 24 is preferably a bell crank lever connected with a link 27, which, in turn, is connected with a pivot arm 28 (see Fig. 8) by the interaction of which the brake band 23 may be clamped about the brake drum 22. In the position shown in full lines at Fig. 8, this brake band is clamped in position, but when released to move in the direction indicated by the arrow the brake releases, permitting the rotation of the brake drum 22, and therewith the shaft 17 and pinions 18 and 19. To effect this rotation of the shaft 17 and the pinions when the brake is released, the falls 29 and 30 from the boat 31 pass through blocks 32 and 33 carried by the davits and extend downwardly, as at 34 and 35 and are passed about winding drums 36 and 37 mounted upon the shaft 17. Manual clutches 38 and 39 are provided for controlling the connection of these drums with the shaft. When rigidly connected, as will normally be the case, the weight of the boat exerted upon the sections 34 and 35 of the falls will be transmitted to the winding drums 36 and 37 and the weight of the boat will therefore rotate the shaft 17, and therewith the pinions 18 and 19, to move the davits upon their pivots 15 and 16 in the direction indicated by the arrows in Figs. 1 and 8, to move from normal to outboard position. The weight of the boat itself, therefore, when exerted upon these drums, serve to swing the davits and the suspended boat outboard. While the tilting of the davits outboard from the weight of the boat is intended to operate at all times, it is obvious, of course, that all mechanisms are subject to failure. In case the davit should fail to swing properly from the action of the weight of the boat, the davit may be swung by a manual rotation of the shaft 17 by applying a crank to said shaft to rotate the pinions 18.

To support the boat in normal carrying or storage position, spaced chocks 40 and 41 are provided supported upon the deck, each

by a pair of uprights 42 rigidly secured to the deck, as indicated, with the chocks pivoted between and to the upper ends of the uprights, as at 43. The opposite ends of the chocks 40 are each supported by a toggle comprising the sections 44 and 45, said sections being preferably arranged in pairs, as indicated in the drawings, the lower pair 45 being pivoted to the deck at 46, and the upper pair 44 pivoted to the chock 40 at 47. To the elbow joint 48 of the toggle a link 49 is pivoted at one end, the opposite end being pivoted to an arm 50 which, in turn, is pivoted to the deck at 51. The second link 52 forms an extension of the link 49, being similarly pivoted to the arm 50 at one end, and at its opposite end to the arm 53, carried rigidly upon the shaft 54. It will be noted, of course, that there are two of the toggle structures, as there are two of the chocks 40 and 41, only one of said structures being described, the other being identical and provided with corresponding numerals. This shaft 54, to which both of the arms 53 are attached, and which actuates both of the toggle structures, is controlled by a manual lever 55. A latch 56 being attached to the deck, and in the specific form shown, adapted to be rotated upon its pivot to the position 56' to release the lever 55, so that said lever may move from the position shown at Fig. 5 to the position shown at Fig. 4. In the position shown at Fig. 5, the chocks 40 and 41 are in position to support the boat 31 thereon, assisted by hooked extremities 57 formed upon the upper ends of the sections 44 of the toggle to engage the keel 58 of the boat.

When the boat is in position upon the chocks and hooks, as shown at 55, it is maintained in such position rigidly and firmly by any approved means such as are ordinarily employed for a like purpose or specifically by means of chains 58 and 59. These chains, preferably four in number, two upon the inboard and two upon the outboard side of the boat, are provided with hooks 60 which hook over the gunwale of the boat. The showing in the drawings of the simple hooks of L-shape is only by way of illustration, and the hooks will be contoured to conform to the shape of the gunwale. The chains 58 and 59 are provided with eye-bolts 61 which extend through the hooks 60 with nuts 62 for exerting tension and binding the boat rigidly upon the chocks. To provide for this tensioning by means of the nuts 62, it is necessary that the opposite ends of the chains 58 and 59 be rigidly connected to some rigid abutment. This connection is preferably by means of links or loops 63 and 64, attached to the normal ends of the chains, which said loops respectively engage hooks 65 and 66. The hook 65 is formed upon, and preferably in-

tegral with, the arm 50, hereinbefore described, and the hook 66 is carried by, and preferably integral with, a similar arm 67, similarly pivoted to the deck at 68. The two arms 50 and 67 are connected by a link 69 so that the said arms move in unison between their limits, as shown at Figs. 5 and 6, respectively. It will be apparent that with the hooks 65 and 66 positioned as shown at Fig. 5, the loops 63 and 64 will be retained by said hooks when the nuts 62 exert tension upon the chains 58 and 59. When the arms 50 and 67 are swung to the position shown at Fig. 6, the loops 63 and 64 are released and cast off, so that the boat 31 theretofore rigidly held in position by said chains is now released. From inspection of Figs. 5 and 6, it will be noted that this casting off is coincidental with the tilting of the chocks 40 and 41, so that by the manipulation of the lever 55 to move it from the position shown at Fig. 5 to the position shown at Fig. 6, the chocks are lowered and tilted, the keel released, and the retaining chains are cast off, whereby the boat swings freely upon the falls. As hereinbefore noted, the weight of the boat upon the falls, acting upon the drums 36 and 37, swings the davits 13 and 14 outboard, so that the releasing of the two levers 55 and 24 permits the boat, by its own weight, to release itself from restraining bonds and to swing itself outboard by the tilting of the davits. Rotation of the shaft 17 will obviously swing the davits similarly outboard, whereby the boat suspended therefrom will assume a position substantially in parallelism with the keel or deck of the vessel. In case of inclination of the deck, it is sometimes desirable to position the boat otherwise than upon such parallelism. This may be accomplished by manipulation of the clutches 38 and 39, or one of them, as occasion may require, whereby the fall may unwind a greater length from the drums 36 or 37, as may be required to properly right the boat. The manipulation of the structure as hereinbefore described will tend to swing the boat outboard and retain it at approximately deck level. It is obvious that at times it would be desirable not to maintain the boat at deck level. For this purpose the lever 24 may be manipulated whereby the boat may be positioned otherwise than at deck level as will be obvious. The other end of the fall, after passing through the blocks 32 and 33, pass also through sheaves 70 and 71 and wind about drums 72 and 73. These drums 72 and 73 are rigidly mounted upon a shaft 74, with clutches 72' and 73' for maintaining said drums rigidly upon the shaft or to rotate freely upon the shaft as occasion makes necessary or desirable, so that the boat 31, now swinging outboard and righted, if necessary, by the manipulation of the clutches 72' and 73', may be lowered to the water by permitting the unreeling of the fall from the drums 72 and 73. For controlling this unwinding a brake control 75 is rigidly connected with the shaft 74 and a brake band 76 passing about said drum is secured at 77 to the deck, and its opposite end attached to the manual lever 78 pivoted to the deck at 79. The latch 80, similar to the latches 26 and 56, is also provided for maintaining this lever 78 in position to exert tension upon the drum brake 75. It will be understood, of course, that the specific type of latches shown at 26 and 56 and 80 are only illustrative of some means for holding the manual levers in tension exerting position, and are no limitation upon the invention, any type of latching or other locking means being fully within the terms of the present application.

As shown in Fig. 9 a modified or alternative means for operating the band brake 76 is disclosed comprising a fixed upright 79' journalling a hand wheel 80' through which extends a screw 78' pivotally connected with said band. While this alternative structure at Fig. 9 is numbered to correspond with the band brake 76 it is obvious that it may like-wise be employed as a structure alternative for operating the band brake 23.

To return the boat from the water after launching, or to withdraw the falls for launching a second boat, the shaft 74, to which the winding drums 72 and 73 are attached, is also provided with means for applying power here shown as the gear 81, with a pinion 82 intergeared therewith, and means for applying to said pinions, diagrammatically illustrated by the manual crank 83, it being understood, however, that any means for applying power is within the scope of the present invention. Also, to return the davits 13 and 14 to their normal positions and to wind the requisite length of fall about the drums 36 and 37, a shaft 17 is provided with a gear 84 with a pinion 85 intergeared therewith, and means for applying power, conventionally shown as the crank 86. While the function of these gearings are for the purposes primarily just stated, it is obvious that their utility will also extend to the actuation of the shaft 17 when it is desirable to use said shaft to rotate manually the pinions 18 and 19 for the purpose of swinging the davit outboard auxiliary to the action of the boat automatically thereon.

To prevent any possible impedance of the proper swinging of the davits by the rotation of the shaft 17, or the unwinding of the drums 36 and 37, means is provided for releasing the shaft from the gear 84, such means being shown conventionally as the manual clutch 87.

In the operation of the device, assuming the boat to be in carrying position, as shown at Figs. 1 to 5, and rigidly secured to the deck by means of the chains 58 and 59, 5 hooked into the hooks 65 and 66 and resting upon the chocks, the lever 55 is released by moving the latch 56. As illustrated at Figs. 5 and 6, the swinging of this manual lever 55 actuates the toggle to drop and tilt the 10 chock, also to throw the hooks 55 and 56 to cast-off position. The chains 58 and 59 now swing free of any connection of the deck and the boat is allowed to swing outwardly, being given an impulse in that direction by the tilting of the chock. The 15 dropping of the boat and the outward impulse is communicated through the falls to the drums 36 and 37, and by the associated shaft 17 to the pinions 18 and 19 swinging the davits from substantially vertical or 20 upright position in the direction indicated by the arrow, so that said davits extend outward and beyond the deck, carrying therewith the boat suspended therefrom. The 25 movement may be accomplished after the boat has been loaded with passengers, or may be accomplished before loading, in which case the boat is retained at substantially deck level for loading. In case of inclination or 30 uneven keel of the vessel, the keel of the boat is righted by a manipulation of either of the clutches 38 or 39. After this, the lever 78 is released from its latch 80, loosening the brake band 76 from the brake drum 75, 35 whereupon the weight of the boat, acting through the fall, rotates the shaft 74, and the drums 72 and 73 unwind sufficient length of the fall to lower the boat to the water. This being accomplished, the fall is, of 40 course, cast off from the boat and the boat rowed away. It is sometimes desirable to return the boat to the deck, and in other cases, it is desirable to return the launching mechanism to initial position for the launching 45 of a second boat. The first step in this, either simply to return the mechanism to launching position, or to return the boat to the deck, is to actuate the drums 72 and 73. In the particular type of mechanism shown 50 this is brought about by manipulating the lever 83, but it is to be understood that any power may be substituted for the manual crank. The boat or tackle having been raised substantially to deck level, the further rotation of the drums 72 and 73 55 is discontinued and the drums are locked by tightening the brake band 76. The requisite length of fall is now wound upon the drums 36 and 37 and the davits returned 60 to upright position by actuating the shaft 17. In the specific type of structure shown in the drawing, this is through the medium of the manual crank 86, but it is to be understood that power from any source may be 65 substituted for this manual crank. If the

boat is still attached to the falls, the boat is swung inboard with the righting of the davits. If no boat is attached, the lowering tackle is swung inboard in position to be attached to another boat, to be launched in 70 like manner.

What I claim and desire to secure by Letters Patent, is:

1. A boat launching mechanism comprising fulcrumed davits, means to support a 75 boat between the davits, a rotatable shaft arranged adjacent the davits, falls from the boat connected with the davits and with the rotatable shaft, means to lower the boat supporting mechanism, means to employ the 80 stress exerted upon the falls by the lowering of the boat, to rotate the shaft, and means to utilize the rotation of said shaft to swing the davits to outboard position. 85

2. A boat launching mechanism, comprising spaced fulcrumed davits, boat supporting mechanism positioned between the davits, rotatable mechanism to swing the davits to outboard position, falls from the boat passing over the davits to said davit 90 rotatable swinging mechanism, and means to lower the boat supporting mechanism to exert the stress of the falls to rotate said davit swinging mechanism. 95

3. A boat launching mechanism comprising spaced davits, a boat supporting structure located between the davits, connected winding drums, a second set of winding drums, blocks carried at the extremities of the davits, falls extending from the boat 100 through the blocks, the opposite ends of the falls being wound about the first and second named drums respectively, means to lower the boat supporting mechanism and impel the boat toward out-board position, 105 means to employ the weight of the released boat to rotate said second mentioned drums, thereby swinging the davits to outboard position, and manual means for controlling the rotation of both sets of drums. 110

4. A boat launching mechanism, comprising davits, segmental racks associated with said davits, pinions engaging the segmental racks, a shaft connecting the pinions, boat supporting mechanism positioned between the davits, blocks carried at the extremities of the davits, falls extending from the boat through said blocks to actuate said shaft, and means to lower said boat supporting mechanism. 115

5. A boat launching mechanism, comprising spaced davits pivoted to swing to outboard position, segmental racks carried by said davits, concentric with their pivoting, pinions engaging the segmental racks, a shaft connecting the pinions, a drum mounted upon the shaft, blocks carried at the extremities of the davits, boat supporting mechanism disposed between the davits, falls extending from the boat through said 125 130

blocks and wound upon said drum, and means to lower said boat supporting mechanism to exert the stress of the falls upon the drum to rotate the pinions and swing 5 the davits outboard.

6. A boat launching mechanism, comprising spaced fulcrumed davits, a shaft journaled adjacent the davits, winding drums carried upon the shaft, a manual brake 10 mechanism for controlling rotation of the shaft and drums, boat supporting mechanism interposed between the davits, a second shaft, means carried by the second shaft for swinging the davits outboard, blocks 15 carried at the extremities of the davits, falls connected with the boat and passing through

the blocks, opposite ends being connected to rotate said shafts respectively, means to lower the boat supporting mechanism and impel the boat toward outboard position 20 and exert stress upon the falls, manual means for releasing the second mentioned shaft when subjected to the stress of the boat, to employ said stress to swing the davits outboard, and manual means for controlling the rotation of the first mentioned shaft to lower the boat after swinging to said outboard position. 25

In testimony whereof he affixes his signature.

CHARLES W. BLAKE.
